DESIGN FOR A HOLDER FOR SPICE CANS
OR SIMILAR ARTICLEMyron D. Markley, Southington, and Joseph M.
Markley, Jr., Meriden, Conn.

Application May 8, 1947, Serial No. 138,916

Term of patent 14 years

(Cl. D80—9)

To all whom it may concern:

Be it known that we, Myron D. Markley and Joseph M. Markley, Jr., citizens of the United States and residing at Southington, county of Hartford, and State of Connecticut, and Meriden, county of New Haven, and State of Connecticut, respectively, have jointly invented a new, original, and ornamental Design for a Holder for Spice Cans or Similar Article, of which the following is a specification, reference being had to the accompanying drawing, forming part thereof.

Fig. 1 is a perspective view of a holder for spice cans or similar article showing our new design;

Fig. 2 is a rear elevational view;

Fig. 3 is a top plan view; and

Fig. 4 is an end elevation.

The broken lines are shown for illustrative purposes only.

We claim:

The ornamental design for a holder for spice cans or similar article, as shown and described.

MYRON D. MARKLEY.
